C. W. Newton

UNITED STATES PATENT OFFICE.

CHARLES W. NEWTON, OF BOSTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

FOLDING MACHINE.

Application filed March 20, 1920, Serial No. 367,420. Renewed February 9, 1923.

This invention relates to machines for finishing the edge of a piece of sheet material and is herein illustrated as embodied in a machine designed to produce so-called 5 French edges on parts of uppers of boots and shoes and to perform similar operations.

It is customary in the manufacture of certain styles of boots and shoes to bind the edges of parts of the uppers with a strip of 10 fabric. To this end such a strip is stitched to the edge of a vamp, quarter or other part which is to be bound, cement is applied to the strip after which the free portion of the strip is folded about the edge of the vamp, quarter 15 or other piece and pressed down so that the cement may hold it firmly in place.

During the folding operation, it is desirable to pull or wipe the free portion of the binding over that portion of itself which is 20 attached to the material so that there may be no looseness or wrinkles in the finished edge, this being true whether or not the binding has been previously pulled out. To this end, the binding-engaging member of the illustrative machine which operates upon the under side of the work (or upon that side of the material to which the binding is attached) is 25 a narrow member of rigid material which is caused to move intermittently in a direction to pull the free portion of the binding over 30 the attached portion thereof.

After the binding has been thus pulled out, it is drawn over the edge of the material. In the illustrated machine, this drawing over 35 or folding operation is performed by a second binding-engaging member which is also rigid and narrow, the two members being located substantially one above the other. By providing members of this kind which cooperate to pull out and fold the binding, the resultant edge is compact and uniform in appearance, and curved edges may readily be operated upon.

These and other features of the invention, 45 including certain details of construction and combinations of parts, will be described as embodied in an illustrative machine and pointed out in the appended claims.

Referring now to the accompanying drawings, 50

Fig. 1 is a perspective of a portion of a machine in which the present invention is

embodied, the outline of the frame of the machine being indicated in dotted lines;

Fig. 2 is a vertical longitudinal section 55 through the lower work-supporting arm of the frame and the mechanism contained therein;

Fig. 3 is a perspective showing more particularly the work-engaging parts of the 60 machine;

Fig. 4 is a set of perspectives of certain parts by which movement of the upper and lower wipers is effected;

Fig. 5 is a section through a piece of work 65 comprising a piece of leather to which a fabric binding strip has been stitched;

Fig. 6 is a section through the same piece of work after the free portion of the binding has been pulled out or "straightened", and 70

Fig. 7 is a section through the same piece of work after it has been operated upon to form a "French edge".

Referring first to Figs. 5, 6 and 7, in the formation of a French edge a binding strip 75 201, usually fabric, is fastened to a part of the upper 203 of a shoe, which is usually leather, by stitches 205. The next operation is to pull out or straighten the binding, as shown in Fig. 6, which may be done by hand 80 or by the use of a machine such as that shown in the patent to McIntire No. 1,322,591. The work in substantially this condition and with a coat of cement applied to the upper side of the binding is then fed to a machine which 85 folds the free portion of the binding about its attached portion and about the edge of the upper material to produce the effect shown in Fig. 7. It has been stated above that after the binding has been pulled out either by 90 hand or by machine, it presents substantially the appearance shown in Figure 6. It should be understood, however, that although the free portion of the binding may be pulled out to the position shown, it will seldom remain 95 exactly in that position, particularly if the preliminary pulling out has been done by hand. There will thus always be some looseness in the locality in which the free portion of the binding extends over the attached portion; and this looseness should be taken up completely in the subsequent operations upon 100 the work. It is one object of the present invention to take up this looseness, whether or

not the binding has been previously pulled out, by exerting a pull upon the binding during the operation of the machine of the present invention, and particularly to provide means for drawing the free portion of the binding about the attached portion and about the edge of the material when sharply curved edges are encountered.

Although the work has thus far been referred to as having a French edge formed upon it, the machine of the present invention is equally well adapted to fold a binding or anything which has the characteristics of a binding over the edge of a piece of material. In this connection it should be noted that the work shown in Figs. 2 and 3 comprises a blank of buckram 301 or other comparatively stiff material one side and the edge of which is covered by a piece of thin leather 303 or other comparatively flexible material, the machine of the present invention being adapted to fold the projecting margin of the leather over the edge of the buckram.

Before proceeding to a detailed description of the construction of the machine, a brief description of its general mode of operation will be given. The margin of the work is fed intermittently over a support 9 by the co-operative movement of an upper feed member 11 and a lower feed member 13, and is guided in such movement by an edge gage 15. The surface of the more flexible component of the work is in contact with the gage, but it is the edge of the less flexible material which determines, in conjunction with the guiding by the operator, the general path of the feed. The feed mechanism operates intermittently upon the work; and during the pauses in the feed a presser-foot 17 holds the work upon the support, said foot having formed on its lower end a thin, flat horizontally extending portion 117 which serves as a creaser or fold guide. The combined foot and creaser is shown in this position in Fig. 3. At this time a folder or wiper 19, hereinafter referred to as the upper wiper or binding-engaging member, is actuated to push the upstanding margin of the more flexible material over the creaser 117. At the same time that the upper wiper 19 is operating as has just been described to push the upstanding margin of the more flexible material to the left, a second wiper 21 (see Fig. 2), hereinafter referred to as the under wiper or binding-engaging member, is moved to the right in such manner as to co-operate with the upper wiper in drawing the more flexible material tightly about the edge of the less flexible material. The presser foot 17 then rises slightly and the wipers are moved away from the work and respectively to the right and to the left so as to be in positions to repeat their co-operating folding movements as soon as the work has been fed forward another step. The feed mechanism now ad-

vances the work one step, and thereafter the presser-foot 17 descends again, and the wipers 19, 21 again make their operative movements. It is desirable, of course, that, after the wipers have operated to form the fold, and the folded margin has been fed past the creaser 117, the fold should be pressed. To this end the upper feed member 11 has fast to it a fold presser or hammer 23 which descends with the descent of the upper feed member and presses or hammers the fold against the work support. In this way the portion of the more flexible material which projects beyond the edge of the less flexible material is progressively folded over and hammered down upon the upper margin of the less flexible material. With this brief description of the general mode of operation of the machine, a detailed description of its construction will now be given.

Referring more particularly to Figs. 1 and 2, the illustrative machine was made from an old and well-known type of sewing machine, the frame and feed mechanism remaining unchanged except as pointed out below, the needle-bar and shuttle having been removed. The frame comprises a work-supporting arm 25 and an overhanging arm 27, there being mounted in the overhanging arm a drive shaft 29 and in the work-supporting arm a counter-shaft 31 which is driven from the drive shaft by double cranks on the respective shafts and connecting links 33. Also mounted in the work-supporting arm is a rock shaft 35 which is oscillated by the drive shaft through an eccentric 37, a connecting link 39 and an arm 41. Fast to the outer end of the counter shaft 31 is an eccentric 43 encircling which is an eccentric strap 45 to an arm on the upper side of which is adjustably fastened by a screw 47 the lower feed-member 13 having teeth on its upper, operative face. The arm on the eccentric to which the lower feed-member is fastened by the screw 47 is pivotally connected by means of a link 49 with an arm 51 formed on the end of the rock shaft 35. Rotation of the shaft 29 will therefore impart to the lower feed member 13 a well-known movement the path of which is in general elliptical. The effect is to cause the member 13 to rise into contact with the under side of the work, to feed the work one step and then descend and return to its first position.

Turning now to the upper feed-member 11 and presser-foot 17, these parts are operated in the following manner: The presser-foot 17 is fast to an upright rod 53, which is vertically slidable in alined bearings formed in the overhanging arm 27, said rod being urged downwardly at all times by a comparatively heavy spring 55 which bears at its upper end against the arm and at its lower end against a collar 57 adjustably

fastened to the rod by a pinch-screw 59. A bracket integral with the collar carries a pivot (not shown) upon which is mounted the hub of a bell-crank lever having a substantially vertical arm 61 and a substantially horizontal arm 63, said hub being held in place on the pivot by a screw 65 which is threaded into one end of the pivot. The horizontal arm 63 is pivoted at its outer end 5 at 67 to the upper end of a rectangular rod 69 to the lower end of which the upper feed-member 11 is adjustably fastened by a screw 71. The arm 69 is permitted a certain amount of swinging movement about the pivot 67 and passes through what amounts 10 to a slot in a portion of the overhanging arm 27. Three sides of the slot are formed by the walls of a recess 73 cut in the arm 27 and the fourth side is formed by a lug 15 75 which is fast to or part of said overhanging arm. A leaf spring 77, attached at its upper end to the rod 69, bears against the forward or left-hand wall of the recess 73 and tends at all times to swing the rod 69 20 into contact with the rear or right-hand wall of the recess, as shown. The upright arm 61 of the bell crank lever referred to above is pivoted at 79 to one end of a link 81 the other end of which is pivoted at 83 to a 25 crank arm 85 which is rigid with a disk 87 on the outer end of the drive shaft 29.

The operation of the feed mechanism is briefly as follows: Assuming that the disk 87 is rotating in the direction indicated by 30 the arrow and that the pressure-foot 17 is resting upon the work so that no further downward movement of the rod 53 is possible, the effect of moving the pivot 83, the link 81 and consequently the upright arm 40 61 to the left will be to raise the rod 69 and consequently the upper feed-member 11, the raising taking place about the pivot 65 which at this time acts as a fixed pivot. As soon, however, as the upright arm 61 has 45 passed its extreme left-hand position and begins to return, the rod 69 and feed-member 11 will be lowered until the downward movement of the feed-member is arrested by contact with the work. As soon as this happens, the pivot 67 will act as a fixed pivot, 50 and the pivot 65, together with the rod 53, will begin to rise against the force of the spring 55. This will continue until the upright arm 61 passes the limit of its right-hand movement and begins its movement to 55 the left again. During this left-hand movement, the rod 53 and pivot 65 will be lowered until the presser-foot 17 again contacts with the work, whereupon the rod 69 and feed member 11 will be raised again, this 60 cycle of movements continuing as long as the shaft 29 rotates. The movements of the various parts of the machine are so timed that the lower feed-member 13 rises to force 65 the work against the lower face of the upper

feed member 11 just as the presser-foot 17 is being raised from the work. The lower feed-member is then moved forward thereby swinging the upper feed-member forward about the pivot 67. As soon as the lower 70 member 13 has completed a feeding movement and descends, the presser-foot 17 is brought down upon the work and the upper feed member 11 raised, whereupon the spring 77 moves it back into the position 75 shown and the cycle is repeated. Whenever it is desired to raise the upper feed-member and presser-foot simultaneously, for example to facilitate removal of a piece of work from the machine, a finger piece 89 80 may be manipulated. The details of the feed mechanism which has thus been described form no part per se of the present invention, and any suitable feed mechanism 85 may be used.

Referring now more particularly to Figs. 2, 3 and 4, the construction of the wipers 19 and 21 and their operating mechanism will be described. The upper wiper 19 is fastened to a strip of spring steel 91 by a screw 93 which passes through a block 95 and is threaded into the spring strip, the strip in turn being fastened by a screw 97 to a slide 99 mounted in a suitable guideway on the work-supporting arm 25. The slide is pivoted at 101 to one end of a link 103 the other end of which is pivoted at 105 to an arm 107 formed on the upper end of a vertical rock-shaft 109, said rock-shaft being angularly movable in a vertical bearing 111 carried by 100 the frame of the machine. The wiper or folder is thus moved over the end of the creaser or fold guide 117 in a path which is substantially parallel to the plane of the work; and the height of the folder may be 105 changed as desired to provide for pieces of work of different thicknesses by turning the screw 127. To the lower end of the vertical rock-shaft is fastened a hub 113 having integral therewith an arm 115. A screw 119, 110 threaded through the arm, is connected by a spring 121 with the frame of the machine and carries a roll 123 which co-operates with a cam 125 fast to the counter-shaft 31.

In order to hold the upper wiper 19 more securely a block 126 is held against its rear end by a screw 128. From this construction it will be evident that rotation of the counter-shaft will cause reciprocation of the slide 99 and with it of the upper wiper 19. 115 With the parts in the positions shown in Fig. 2, the wiper 19 is in its extreme right-hand position. Presently it will be moved to the left to lay the margin of the more flexible material 303 over the edge of the less 120 flexible material 301. If it were permitted to return to the right in the same path in which it moved to the left, it would tend, particularly by reason of the teeth on its lower face, to pull back the margin of the 125 130

more flexible material 303. In order to prevent such an undesirable occurrence, means are provided for raising the wiper 19 when it has completed the folding operation and for holding it raised during the retracting movement. To this end a screw 127 threaded into the upper end of a push-pin 129 bears against the under side of the spring strip 91, said pin being vertically slidable in a bore 130 in a stationary block 131 and resting at its lower end upon a cam 133 fast to the shaft 31. Rotation of the shaft 31, therefore, causes the upper wiper 19 to be moved first to the left to fold the work, then to be raised and retracted and then to be lowered into the position shown. In order to add to the strength of the spring strip 91, a leaf spring 135 is fastened to it by the same screw 97 which fastens the strip to the slide 99. And in order to compel the wiper 19 to be raised whenever the finger piece 89 is manipulated to raise the presser-foot 17, the block 95 has an outwardly extending arm which overlies a finger 137, said finger being fastened to the presser-foot by a screw 139.

The under wiper 21 is fast to a box yoke 141 which is mounted on the stationary block 131 so as to permit its front and side portion to be movable both angularly and bodily with respect to the block. To this end the yoke embraces the upper squared portion of the block, the rear bar 145 of the yoke being received in a guideway 147 formed between projecting ears 149 on the block and being pivoted at its ends at 151, 153 to the side bars or arms of the yoke. The yoke is moved to the right (see Fig. 2) by the rising of a push-pin 155 in a bore 156, the upper beveled end of the pin co-operating with the beveled end of a projection 157 on the rear bar 145 of the yoke. A spring 159 extending into a socket in the work-supporting arm 25 of the machine tends at all times to move the yoke, and with it the wiper 21, to the left. The push-pin 155 is raised at the proper time by a cam 161 on the counter-shaft 31. The combined action of the push-pin 155 and the spring 159 thus serves to move the wiper 21 first to the left and then to the right. In its movement to the right, the wiper should contact with the work and thereby aid the wiper 19 (which at that time is moving to the left) to form a tight fold. In its return movement (to the left) it should be out of contact with the work. To this end it is raised and lowered at the proper times about the axis of the pivot 151 by a third push-pin 163 which is vertically slidable in a bore 165 in the block 131, said pin having an arm 167 the upper face of which contacts with the head of a small screw 169. This screw is loose in a socket in the front bar of the yoke 141 and does not serve the ordinary purpose of a screw. It is in reality merely a contact member, and carries a

coiled spring 171 so that the under wiper 21 is raised yieldingly when the push-pin 163 is raised.

Referring again to the upper feed-member 11 and to the presser-foot 17, the feed-member has fast to or integral with it the hammer or fold presser 23 which operates to press or hammer the folded margin of the binding or similar member down upon the margin of the body material; and the presser-foot has the thin horizontal extension 117 which serves as a creaser over which the margin of the binding is folded. In this connection it should be noted that the extent to which the presser-foot 17 is raised is slight as compared with that of the upper feed member 11 and hammer 23. The general mode of operation of the machine has been described above. In particular it should now be noted that the binding-engaging members 19, 21 are made of rigid material, are comparatively narrow and execute their operative movements during the pauses in the intermittent feed movements. With such a construction and mode of operation the drawing of the binding about the edge to be bound is thorough so that wrinkles or bunches which have tended to occur with prior machines are obviated, and the folding of convex curves, particularly of abrupt curves commonly known as "corners" which occur for example in button flies and in the small reinforcing article shown in Figs. 2 and 3, is greatly facilitated. As has been explained, the machine is adapted to fold a strip of binding, such as that shown at 201 in Figs. 5, 6 and 7, or a piece of covering material such as that shown at 303 in Fig. 3 or to perform similar operations. In order to promote brevity the work, throughout the claims, will be referred to as a piece of material to which a piece of binding is attached.

Although the invention has been set forth as embodied in a particular machine and has been described in connection with particular kinds of work, it should be understood that the present invention is not limited in the scope of its application to the particular machine nor to operation upon the particular kinds of work which have been shown and described.

Having thus described my invention, what I claim as new and desire to secure by Letters Patent of the United States is:

1. A machine for operating upon a piece of work which consists of a piece of material to which a piece of binding is attached, having in combination, a support for the work, means for feeding the work over the support, a rigid binding-engaging member located to operate upon one side of the work, a second rigid binding-engaging member located to operate on the other side of the work, and means for causing said members to engage opposite sides of the work and to

move in opposite directions to wrap the binding about the edge of the material.

2. A machine for operating upon a piece of work which consists of a piece of material to which a piece of binding is attached, having in combination, a support for the work, means for feeding the work over the support, a rigid binding-engaging member located to operate upon one side of the work, a second rigid binding-engaging member located to operate on the other side of the work, and means including a spring for causing said members to engage opposite sides of the work yieldingly and to move in opposite directions to wrap the binding about the edge of the material.

3. A machine for operating upon a piece of work which consists of a piece of material to which a piece of binding is attached, having in combination, a support for the work, a binding-engaging member located to operate upon one side of the work, a second binding-engaging member located to operate upon the other side of the work, and means for reciprocating said members in opposite directions to draw the binding about the edge of the material.

4. A machine for operating upon a piece of work which consists of a piece of material to which a piece of binding is attached, having in combination, a support for the work, a narrow binding-engaging member located to operate upon one side of the work, a second narrow binding-engaging member located to operate upon the other side of the work and substantially beneath the first-named member, and means for reciprocating said members in opposite directions to draw the binding about the edge of the material.

40 5. A machine for operating upon a piece of work which consists of a piece of material to which a piece of binding is attached, having in combination, a support for the work, a yielding binding-engaging member located to operate upon one side of the work, a second yielding binding-engaging member located to operate upon the other side of the work, and means for reciprocating said members in opposite directions to draw the binding about the edge of the material.

55 6. A machine for operating upon a piece of work which consists of a piece of material to which a piece of binding is attached, having in combination, a support for the work, a yielding binding-engaging member located to operate upon one side of the work, a second yielding binding-engaging member located to operate upon the other side of the work and substantially beneath the first-named member, and means for reciprocating said members in opposite directions to draw the binding about the edge of the material.

7. A machine for operating upon a piece of work which consists of a piece of material to which a piece of binding is attached

having, in combination, a support over which the work is fed intermittently with the side to which the binding is attached resting upon the support, a binding-engaging member located beneath the work, means for moving said member back and forth in a substantially horizontal direction transversely of the direction of feed movement of the work to pull the free portion of the binding out over the attached portion, and means for folding the pulled-out binding over upon the body of the work.

8. A machine for operating upon a piece of work which consists of a piece of material to which a piece of binding is attached, having in combination, a support for the work, means for feeding the work intermittently over the support, a binding-engaging member located to operate upon one side of the work, a binding-engaging member located to operate upon the other side of the work, and means for causing the members to engage the work on opposite sides during the pauses in the intermittent feed movements and reciprocate in opposite directions and to be disengaged from the work between said movements.

9. A machine for operating upon a piece of work which consists of a piece of material to which a piece of binding is attached, having in combination, a support for the work, means for feeding the work intermittently over the support, a binding-engaging member located to operate upon one side of the work, a binding-engaging member located to operate upon the other side of the work, and yielding means for causing the members to engage the work on opposite sides during the pauses in the intermittent feed movements and to be disengaged from the work between said movements.

10. A machine for operating upon a piece of work which consists of a piece of material to which a piece of binding is attached, having in combination, a support, means for feeding the work intermittently over the support, a rigid binding-engaging member adapted to operate upon one side of the work, a second rigid binding-engaging member adapted to operate upon the other side of the work, and means for imparting operative movements to said members in opposite directions to wrap the binding about the edge of the material.

11. A machine for operating upon a piece of work which consists of a piece of material to which a piece of binding is attached, having in combination, a support, means for feeding the work intermittently over the support, a rigid binding-engaging member adapted to operate upon one side of the work, a second rigid binding-engaging member adapted to operate upon the other side of the work, means for imparting operative movements to said members in opposite di-

rections to wrap the binding about the edge of the material, and yielding means for holding the members in contact with the work during their work-engaging movements.

- 5 12. A machine for operating upon a piece of work which consists of a piece of material to which a piece of binding is attached, having in combination, a support for the work, means for feeding the work, a binding-engaging member for laying the projecting portion of the binding over the edge of the material, and mechanism operating so to move the member and then to move it away from the plane of the work in a path at an 15 angle to the path of its first movement and return it into a position to permit the movements to be repeated.

13. A machine for operating upon a piece of work which consists of a piece of material 20 to which a piece of binding is attached, having in combination, a support for the work, means for feeding the work, a member for engaging that part of the binding which is in superposed relation to the material, and 25 mechanism operating to move the member into contact with the binding, to move it along in contact with the binding toward the edge of the material and then to move it away from the work and return it into position 30 to permit the movements to be repeated.

14. A machine for operating upon a piece of work which consists of a piece of material to which a piece of binding is attached, having in combination, a support for the work, means for feeding the work, a binding-engaging member located above the work, a second binding-engaging member located below the work, a drive shaft located below 40 the plane of the work support, cams on said shaft, and mechanism responsive to movement of said cams for causing the members to engage opposite sides of the work and to move in opposite directions to wrap the binding about the edge of the material.

45 15. A machine for operating upon a piece of work which consists of a piece of material to which a piece of binding is attached, having in combination, a support for the work, means for feeding the work intermittently over the support, a creaser having its operative end substantially in line with the edge of the material, a wiper located above the work, means for operating the wiper to fold the margin of the binding over the edge 50 of the material and that of the creaser during the pauses in the feed, and means for pressing the fold.

60 16. A machine for operating upon a piece of work which consists of a piece of material to which a piece of binding is attached, having in combination, a support for the work, means for feeding the work intermittently over the support, a creaser having its operative end resting upon the upper side of and 65 substantially in line with the edge of the

material, a wiper, means for operating the wiper to fold the margin of the binding over the edge of the material and that of the creaser, a second wiper, means for causing the second wiper to move along the under side of the work substantially in the plane of the support and to cooperate with the first wiper and with the creaser in forming the fold, and means for pressing the fold.

70 17. A machine for operating upon a piece of work which consists of a piece of material to which a piece of binding is attached having, in combination, a support over which the work is fed intermittently, a binding engaging member movable along the under side of the material to pull out the binding, a second binding engaging member movable to bend the binding over the edge of the material, and means for causing said members to operate intermittently upon the binding 80 during the pauses in the intermittent feed movements of the work.

85 18. A machine for operating upon a piece of work which consists of a piece of material to which a piece of binding is attached, having in combination, a support for the work, means including a combined feed member 90 and fold presser for feeding the work, a binding-engaging member located above the work, a second binding-engaging member 95 located below the work, and means for operating said members in different directions.

100 19. A machine for operating upon a piece of work which consists of a piece of material to which a piece of binding is attached, having in combination, a support for the work, means including a combined feed member and fold presser for feeding the work, a binding-engaging member located above the work, a second binding-engaging member located below the work, and means for reciprocating said members in opposite directions.

105 20. A machine for operating upon a piece of work which consists of a piece of material to which a piece of binding is attached, having in combination, a support for the work, means including a combined feed member and fold presser and a combined presser-foot and creaser for feeding the work intermittently, binding-engaging members located to operate respectively on opposite sides of the work, and means for operating said members.

110 21. A machine for operating upon a piece of work which consists of a piece of material to which a piece of binding is attached, having in combination, a support for the work, means including a combined feed member and fold presser and a combined presser-foot and creaser for feeding the work intermittently, rigid binding-engaging members located to operate respectively on opposite sides of the work, and means for operating said members.

22. A machine for operating upon a piece of work which consists of a piece of material to which a piece of binding is attached, having in combination, a support for the work, means including a combined feed member and fold presser and a combined presser-foot and creaser for feeding the work intermittently, rigid binding-engaging members located to operate respectively on opposite sides of the work, and means for reciprocating said members. 70
23. A machine for operating upon a piece of work which consists of a piece of material to which a piece of binding is attached, having in combination, a support for the work, means for feeding the work over the support, a binding-engaging member located to operate upon one side of the work, a second binding-engaging member located to operate on the other side of the work, and means for causing said members to engage opposite sides of the work intermittently and to be moved simultaneously in opposite directions during such intermittent engagement. 75
24. A machine for operating upon a piece of work which consists of a piece of sheet stock to which a piece of binding is attached, having in combination, a support for the work, means for feeding the work over the support, a binding-engaging member of rigid material located to operate upon the under side of the work, means for moving said member in a direction to pull the free portion of the binding tightly over the attached portion thereof, a member of rigid material operating in a locality above the body of the stock for folding the free portion of the binding over upon the upper side of the stock, and means for pressing the fold. 80
25. A machine for operating upon a piece of work which consists of a piece of material to which a piece of binding is attached having, in combination, a support for the work, means for feeding the work intermittently over the support, a wiper, means for causing the wiper to move intermittently along the under side of the work substantially in the plane of the support during the pauses in the intermittent feed to force the free portion of the binding over the attached portion, a folder, means for causing the folder to bend the margin of the binding about the edge of the material to form a fold, and means for pressing the fold. 85
26. A machine of the class described having, in combination, a support for the work, means for feeding the work intermittently over the support, a binding-engaging member movable forward and backward outwardly and inwardly of the edge of the work in a path located beneath the work, means operating during the pauses in the intermittent feed movements for moving the binding-engaging member forward to draw a free portion of the binding over that portion of itself which is attached to the material and for moving said member backward during the feed movements into position to be moved forward again, a second binding-engaging member, means also operating during the pauses in the intermittent feed movements for causing said member to bend the binding about the edge of the material to form the fold, and means for pressing the fold. 90
27. A machine of the class described having, in combination, a support for the work, means for feeding the work intermittently over the support, a narrow binding-engaging member of rigid material; means operating during the pauses in the intermittent feed movements for moving the binding engaging member in a direction substantially transverse to the direction of feed and in a path located beneath the work to draw a free portion of the binding over that portion of itself which is attached to the material, a presser-foot, means also operating during the pause in the intermittent feed for causing the presser foot to engage the material above the binding-engaging member to hold the work down against the action of the binding-engaging member, a second binding-engaging member, means also operating during the pause in the intermittent feed movements for causing said member to bend the binding about the edge of the material to form the fold, and means for pressing the fold. 95
28. A machine for operating upon a piece of work which consists of a piece of material to the edge of which a piece of binding is attached having, in combination, a support over which the work is fed with the side to which the binding is attached resting upon the support, a binding-engaging member located beneath the work and means for moving said member back and forth in a direction at an angle to the direction of feed movement of the work, to pull the free portion of the binding over that portion of itself which is attached to the material. 100
29. A machine for operating upon a piece of work which consists of a piece of material to which a piece of binding is attached having, in combination, a support for the work, a binding-engaging member adapted to move in a path located upon one side of the material to pull the free portion of the binding over the attached portion thereof, a second binding-engaging member adapted to fold the free portion of the binding over the edge of the material, and means for moving said members back and forth in different directions. 105
30. A machine for operating upon a piece of work consisting of a piece of sheet material to which a strip of binding is attached having, in combination, a support over which the work is fed with that side of the material to which the binding is attached in contact 110
- 120
- 125
- 130

with the support, a gage adapted to engage the free portion of the binding and bend it upwardly, a binding-engaging member provided with a serrated operative face and means for causing said member to move in a path substantially parallel to the plane of the body portion of the work to bend the free portion of the binding over the margin of the material.

31. A machine for operating upon a piece of work which consists of a piece of material to which a strip of binding is attached having, in combination, a support over which the work is fed intermittently, mechanism for intermittently pulling out successive free portions of the strip over successive attached portions thereof, mechanism for intermittently folding the successively pulled-out portions about the edge of the material, and mechanism for pressing the folded portions into contact with the margin of the material.

32. A machine for operating upon a piece of work which consists of a piece of material to which a piece of binding is attached having, in combination, a support for the work, means for feeding the work intermittently over the support, a member for engaging that part of the binding which is in superposed relation to the material, mechanism operating to move the member into engagement with the binding, to move it along in contact with the binding toward the edge of the material during the pauses in the intermittent feed, and then to move it back into position to permit the movements to be repeated.

33. A machine for operating upon a piece of work which consists of a piece of material to which a strip of binding is attached having, in combination, a support, means for feeding the material intermittently over the support with the side to which the binding is attached resting upon the support, a binding-engaging member located beneath the work, means for moving said member back and forth in a direction at an angle to the direction of feed movement of the work to pull a free portion of the binding over that portion of itself which is attached to the material, a presser for holding the material against the binding-engaging member during the pulling operation, and means for intermittently operating the presser.

34. A folding machine having, in combination, a support for the work, means for feeding the work, a folder, means for moving the folder in a path substantially parallel to the plane of the work transversely of the direction of feed movement, and means for adjusting the folder to locate its path of movement nearer to or farther from the plane of the work.

35. A folding machine having, in combination, a support over which the work is fed, a folder, means for moving the folder

in a path substantially parallel to the plane of the work, means for adjusting the folder to locate its path of movement nearer to or farther from the plane of the work, and a fold presser located in the rear of the folder.

36. A folding machine having, in combination, a creaser having a free end adapted to determine the line of the fold, a folder, means for moving the folder in a right line path substantially parallel to the plane of the work across the free end of the creaser to fold the margin of the work about said end, and means for feeding the work past the creaser and the folder.

37. A folding machine having, in combination, a creaser having a free end adapted to determine the line of the fold, a folder, means for moving the folder in a right line path substantially parallel to the plane of the work across the free end of the creaser to fold the margin of the work about said end, and means for feeding the work intermittently past the creaser and the folder, the folding of the margin taking place during the pauses in the intermittent feed movements.

38. A folding machine having, in combination, a creaser having a free end adapted to determine the line of the fold, a folder, means for moving the folder in a right line path substantially parallel to the plane of the work across the free end of the creaser to fold the margin of the work about said end, and means for feeding the work past the creaser and the folder, and for pressing the fold.

39. A folding machine having, in combination, a support for the work, a creaser having a free end, a folder, means for moving the folder intermittently in a right line path substantially parallel to the plane of the work across the free end of the creaser to fold the margin of the work along a line determined by the locality at which the free end of the creaser engages the work, a combined feed member and fold presser, and means for operating said combined member to feed the work intermittently between the folding operations.

40. A machine for operating upon a piece of work which consists of a piece of sheet material to which a strip of material is attached having, in combination, a support over which the work is fed intermittently, a creaser having its operative end adapted to register with the desired line of fold in the work, a folder located above the plane of the work, means for moving the folder transversely of the direction of feed movement over the edge of the creaser to fold the margin of the work during the pauses in the feed, and means for pressing the fold.

41. In a folding machine, in combination, folding instrumentalities comprising a member having a fold-determining free end, a

- folder movable in a path located above the plane of the work across the free end of said member to fold the work thereabout, means for moving said folder, and means for advancing the work past said instrumentalities.
42. In a folding machine, in combination, folding instrumentalities comprising a member having a fold-determining free end, a folder movable in a right line across the free end of said member to fold the work thereabout, means for moving said folder, and means for advancing the work past said instrumentalities.
43. In a folding machine, in combination, folding instrumentalities comprising a fold-determining member, a folder movable in a right line to fold the work about said member, means for moving said folder, and means for advancing the work past said instrumentalities.
44. A folding machine having, in combination, a wiper for wiping a strip across the edge of a sheet of material to one face of which, along the said edge, the strip is secured, a retainer for retaining the sheet against movement acting upon the other face of the sheet, means for folding the strip around the said edge, and means for pressing the strip into even contact with the said other face of the sheet.
45. A machine of the class described having, in combination, a wiper and a spring-pressed retainer cooperating to wipe a strip across the edge of a sheet of material to which it is secured, the wiper and the retainer being constructed and arranged to act at oppositely disposed points on opposite faces of the sheet.
46. A folding machine having, in combination, a wiper for wiping material, a retainer adapted to clamp the material against the wiper, means for feeding the material, and means whereby the wiper and the retainer release their hold upon the material upon the feeding means commencing to feed the material.
47. A machine for folding a strip around the edge of a sheet of material to one face of which, along the said edge, an edge of the strip is secured so that the sheet and the strip extend from the secured-together edges at an angle to each other, the said machine having, in combination, a wiper for wiping the strip across the secured-together edges, means for imparting a four-way motion to the wiper, and means for pressing the strip against the other face of the sheet.
48. A machine for wiping a strip across the edge of a sheet of material to one face of which, along the said edge, an edge of the strip is secured so that the sheet and the strip extend from the secured-together edges at an angle to each other, the said machine
- having, in combination, a wiper for wiping the strip across the secured-together edges, and means for imparting a four-way motion to the wiper.
49. A folding machine having, in combination, a support for the work, means for feeding the work, a folder independent of the feeding means, means for moving the folder in a path substantially parallel to the plane of the work transversely of the direction of feed movement, and means for adjusting the folder to locate its path of movement nearer to or farther from the work support.
50. A folding machine having, in combination, a support for the work, means for feeding the work, a folder, means for moving the folder back and forth in a path substantially at right angles to the direction of feed of the work, and means for adjusting the folder to locate its path of movement nearer to or farther from the plane of the work.
51. A machine for folding a strip around the edge of a sheet of material to one face of which, along the said edge, an edge of the strip is secured, having, in combination, means for preliminarily determining the line of fold in the strip and folding the strip around the secured-together edges along the predetermined line, and means for pressing the folded strip into contact with the other face of the sheet along the predetermined line.
52. A machine for folding a strip around the edge of a sheet of material to one face of which, along the said edge, an edge of the strip is secured, the said machine having, in combination, means for successively preliminarily determining successive portions of a line of fold in the strip and folding the successive portions of the strip around the secured-together edges along the said successive portions of the predetermined line, and means for successively pressing the successively folded portions of the folded strip into contact with the other face of the sheet along the predetermined line.
53. A machine for operating upon a piece of work which consists of a piece of sheet material to which a strip of binding is attached having, in combination, a creaser for determining the line of fold, means for feeding the work intermittently past the creaser, means co-operating with the creaser for intermittently and progressively folding successive portions of the strip along the line of fold determined by the creaser, and means for intermittently and progressively pressing the successive portions.
- In testimony whereof I have signed my name to this specification.

CHARLES W. NEWTON.

CERTIFICATE OF CORRECTION.

Patent No. 1,725,929.

Granted August 27, 1929, to

CHARLES W. NEWTON.

It is hereby certified that error appears in the printed specification of the above numbered patent requiring correction as follows: Page 3, line 35, for the compound word "pressure-foot" read presser-foot; same page, line 101, beginning with "The" strike out all to and including the number and period "127." in line 108; page 4, line 16, after the period insert "The wiper or folder is thus moved over the end of the creaser or fold guide 117 in a path which is substantially parallel to the plane of the work; and the height of the folder may be changed as desired to provide for pieces of work of different thicknesses by turning the screw 127.; and that the said Letters Patent should be read with these corrections therein that the same may conform to the record of the case in the Patent Office.

Signed and sealed this 21st day of October, A. D. 1930.

(Seal)

M. J. Moore,
Acting Commissioner of Patents.
